UNITED STATES PATENT OFFICE.

JACOB RANZ, OF ST. LOUIS, MISSOURI, ASSIGNOR TO E. W. GROVE, OF ST. LOUIS, MISSOURI.

HOSE-TOE-PROTECTOR-FORMING MACHINE.

1,030,920.

Specification of Letters Patent.

Patented July 2, 1912.

Application filed July 10, 1911. Serial No. 637,844.

To all whom it may concern:

Be it known that I, JACOB RANZ, a citizen of the United States, residing at St. Louis, Missouri, have invented a certain new and useful Improvement in Hose-Toe-Protector-Forming Machines, of which the following is a full, clear, and exact description, such as will enable others skilled in the art to which it appertains to make and use 5 the same, reference being had to the accompanying drawings, forming part of this specification, in which—

Figure 1 is a side elevation of a machine of my improved construction, parts thereof being shown in vertical section. Fig. 2 is 15 a view of the blank or section of material from which a hose toe protector is formed by my improved machine. Fig. 3 is a side elevation of a hose toe protector formed and 20 shaped by my improved machine. Fig. 4 is an end elevation of the machine looking in the direction indicated by the arrow 4 Fig. 1. Fig. 5 is a plan view of a portion 25 of the former of my improved machine. Fig. 6 is a vertical section taken on the line 6—6 of Fig. 5. Fig. 7 is an elevation of the 30 parts seen looking in the direction indicated by the arrow 7, Fig. 5. Fig. 8 is an enlarged section taken on the line 8—8 of Fig. 1 and showing a portion of the forming means. Fig. 9 is an elevation of a sliding support or head which occupies the packing tube or 35 housing into which the completed protectors are packed.

This invention relates to a machine for forming hose toe protectors, and packing the same into tubular containers.

The hose toe protector formed by my improved machine is preferably made from 40 thin material, such as paper, and is pressed into the form of a cup or a short tube closed at one end, and when in use said hose toe protectors are positioned on the great toe beneath the hose for the purpose of preventing 45 the rapid wear of the hose at the point occupied by the forward portion of the great big toe.

The object of my invention is to provide 50 a simple, inexpensive machine, which can be operated with little power and which will very rapidly form the hose toe protectors from circular blanks of thin material, which are automatically fed to the machine in any suitable manner, and which machine packs

the completed protectors in nested form 55 within suitable tubular containers.

To the above purposes my invention consists in certain novel features of construction and arrangement of parts hereinafter more fully described and claimed. 60

Referring by numerals to the accompanying drawings, 1 designates a suitable base on which is fixed a pair of upright brackets 2 and 3, which latter are provided at their upper ends with aligned bearings 4 and 5. Mounted to slide through the bearing 4 is a rod 6, and a corresponding rod 7 is mounted to slide through the bearing 5. The adjacent ends of the rods 6 and 7 are rigidly fixed in any suitable manner to the opposite 65 side of an upright block 8 having a vertically disposed slot 9.

Fixed on the base 1 between the brackets 2 and 3 and to one side thereof is a bracket 10 having a bearing 11 at its upper end, and 70 journaled for rotation in said bearing 11 is a shaft 12, the same being disposed at right angles to the rods 6 and 7. Loosely mounted on the outer end of this shaft 12 is a pulley 13 and positioned on said shaft adjacent said pulley is a clutch 14 of any suitable construction adapted for locking the pulley to said shaft. 75

Fixed on the shaft 12 adjacent the inner ends of the rods 6 and 7 is a cam 15 having 80 a low portion 16, a high portion 17 and a shoulder 18 between said low and high portions.

Journalized on a pin or trunnion projecting from the outer face of the cam 15 is a roller 90 19 which occupies and operates through the slot 9 in the block 8. 20 designates a sleeve positioned in front of the bearing 4, and through which sleeve the forward end of the rod 6 operates. The forward end of this 85 sleeve 20 is in the shape of a truncated cone 21, and the surface of this forward end is provided with a series of radially disposed ribs 22.

Mounted to slide freely on the forward 100 end of the sleeve 20 is a collar 23 provided with a longitudinally disposed slot 24, the forward end of which extends laterally a short distance as designated by 25. A pin or screw 26 passes through the slot 24 and 105 is seated in the forward portion of the sleeve 20. This construction permits the sleeve 20 and collar 23 to have sliding movement rela-

tive to one another for a predetermined distance, and it also permits these parts to have a slight rotary movement relative to one another when the pin or screw 26 passes 5 into the laterally extending portion 25 of the slot 24.

A nut 27 is screw seated upon the threaded rear end of the sleeve 20, and interposed between said nut and a shoulder on the collar 10 23 is an expansible coil spring 28. One end of a horizontally disposed arm 29 is rigidly fixed in any suitable manner to the rear end of the sleeve 20 which arm extends rearwardly past the bearing 4, and adjustably 15 positioned on the rear end of the arm is a plate 30 carrying an anti-friction roller 31 which travels upon the periphery of the cam 15.

Projecting laterally from the arm 29 is 20 a pin 32, carrying on its outer end a roller 33 which latter normally occupies a horizontally disposed slot 34 formed in the upper portion of a standard 35, and the forward end of this slot 34 is extended downward as 25 designated by 36.

37 designates a standard fixed to the base 1 in front of the standard 2, and mounted in the upper end of said standard 37 is a tubular bearing 38. Loosely mounted in 30 the rear end of this bearing 38 is a former head 39 through which is formed a conical opening 40, the surface of which is provided with a series of radially arranged grooves 41 adapted to receive the ribs 22 on the forward 35 end of the sleeve 20. This head 39 normally occupies a position immediately in front of the collar 23, and formed in the outer face of said head 39 is a series of radially arranged grooves 42, which are adapted to 40 receive corresponding radially arranged ribs 43, formed on the outer face of the collar 23.

44 designates a U-shaped member carried by the head 39 for supporting the blanks of material X from which the toe guards 45 are formed, when said blanks are first fed into position between the collar 23 and head 39.

45 designates a housing in the form of a paper tube one end of which is applied to 50 the forward end of the tubular bearing 38, and the hose toe protectors after being formed by the machine are forced through the tubular bearing 38 into the packing tube 45. In order to support the forward one of 55 the protectors when the same is forced into the packing tube 45, and to cause said protectors to nest within said packing tube a head 46 is provided which head is carried upon the rear end of a rod 47, and said rod 60 is inserted through the packing tube 45 when the latter is fitted onto the tubular bearing 38. The outer portion of this rod 47 is mounted to slide in a suitable bearing 48, and fixed on said rod is a collar 49.

65 50 designates a bar which is arranged to

slide through suitable bearings on the brackets 3 and 37 and projecting upward from the rear end of this bar is an arm 50^a the upper end of which is bifurcated and engages the rod 47 to the rear of the collar 49. 70

A portion of the top edge of the bar 50 is notched as designated by 52 and adapted to engage with these notches is a pawl 53 carried by the yoke 8. Plate 54 is positioned immediately above the notched portion of the bar 50, said plate being supported by a suitable standard 55 extending upward from the base 1. The forward end of the rod 6 is provided with a top 6^a of rubber, leather or analogous material. During the reciprocation of the yoke 8 its lower end has sliding bearing between a pair of longitudinally disposed ribs 1^a formed on the base 1 between the uprights 2 and 3. 80

The operations incident to the formation of hose toe protectors with the machine just described is as follows: A belt is applied to the pulley 13 and when the clutch 14 is thrown in the shaft 12 and parts carried thereby are rotated in the direction indicated by the arrow a, Fig. 1. The roller 19 moving from its lowermost point upwardly and rearwardly moves the yoke 8 together with the rods 6 and 7 rearwardly, and during this rearward movement of the rod 6 the sleeve 20 mounted on the forward end of said rod 6 will by reason of its frictional engagement with said rod be drawn rearwardly until its rear end strikes against the bearing 4. At this point in the operation 90 of the machine, a circular section of thin material X as shown in Fig. 2 is fed into the space between the clamping collar 23 and the head 39, said blank being supported by the member 44. During the first part of the forward movement of the rods 6 and 7, and the yoke 8, due to the movement of the roller 19 through the slot of said yoke, the sleeve 20 carrying the collar 23 will by reason of the frictional engagement between 100 said sleeve and the rod 6 be moved forward, thereby clamping the edge of the blank between the adjacent faces of the collar 23 and head 39. The radially arranged ribs 43 formed on the outer face of the collar 23 will force the edge of the blank into the corresponding grooves 42, thereby creasing the edge of the blank. During the movements of the parts just described the roller 31 is 110 bearing upon the low portion 16 of the cam 15 and after the collar 23 has been moved forward to clamp the edge of the blank, the cam 15 is rotated so that a part of its high portion immediately in front of the shoulder 18 bears against the roller 31, thereby moving the same, together with the plate 30 and arm 29 in a forward direction, and as said plate 29 is rigidly fixed to the sleeve 20 said sleeve will be moved forward through the 120 collar 23, and this movement slightly com-

115

120

125

130

presses the spring 28, thereby storing power therein. During the movements just described the forward portion of the rod 6 moves through the sleeve 20, and the tip 6^a on the forward end of said rod engages the central portion of the blank and moves the same into the forming head 39, thereby gradually withdrawing the edge of the blank from its position between the coinciding faces of the head 39 and collar 23, which latter is held against the forming head by the power stored in the coil spring 28. At this point in the operation the roller 31 traveling against the periphery of the cam 15 rides over the shoulder 18 thereon, and after said roller rides beyond this shoulder, and onto the high portion 17 of the cam, the sleeve 20 is permitted to move rearwardly a slight distance corresponding to the height of the shoulder 18, and at this instant the roller 33 carried by the pin 32 which has been moving forward through the slot 34 rides into the downwardly extending forward end 36 of said slot, thereby slightly moving the bottom of the finger 32, and plate 29, and consequently imparting slight rotary motion to the sleeve 20. During this slight rotary motion of the sleeve 20 the laterally extended forward end 25 of the slot 24 accommodates the screw 26 which is seated in said sleeve 20, and thus the collar 23 does not rotate with the sleeve 20. At this point of the operation the conical forward end of the sleeve 20 has been moved forward into the forming head 39, thereby drawing the edge of the blank X out from between the face of said head, and the corresponding face of the collar 23, which edge as heretofore described is creased or corrugated by means of the radially disposed ribs 43, and corresponding radial grooves 42. The slight rotary motion imparted to the sleeve 20, just described, tends to fold down the radially disposed creases formed around the edge of the blank, and these creases are caused to enter radially disposed grooves 41 within the forming head. These creases or folds designated by Z Fig. 3 have the greatest width at the extreme outer edge of the blank, and said fold or crease gradually decreases toward the center of the blank, and thus an approximately cup or thimble shaped protecting device is formed, which is of such size and form as to fit snugly upon the great toe when positioned thereon. After the protecting device has thus been formed it is forced into the tubular bearing 38 and as succeeding protectors are formed they are nested one within the other and are forced forward through the tubular bearing against the head 46.

In order to permit the nested protectors to pass into the packing tube 45 the head 46 is gradually moved rearwardly through said

packing tube by means of the pawl 53 which at the end of the forward stroke of the yoke 8 passes off the plate 54, engages between the teeth 52 on the top of the bar 50 and moves said bar a short distance forward, and this movement is transmitted to the rod 47 carrying the head 46, by means of the arm 50^a carried by said bar 50, and engaging the collar 49. Thus the head 46 serves as a yielding support for the forward one of the series of protectors packed within the tube 45, and provides means whereby said protectors are tightly packed in nested form. During the rearward movement of the yoke 8 the rods 6 and 7 move rearwardly through the bearings 4 and 5 and the sleeve 20 and parts carried thereby are drawn rearwardly by reason of the frictional engagement between said sleeve and the rod 6. During this rearward movement the roller 33 carried by the pin 32 travels to the rear end of the slot 34 and the pawl 53 carried by the yoke 8 moves over the top of the plate 54.

A machine of my improved construction is comparatively simple, is very compact, can be operated with little power, and very rapidly performs the work of forming thimble shaped hose toe protectors, and packs the same in nested form in suitable tubular packages.

I claim:

1. In a machine of the class described, a forming head having a conical aperture, a second forming head having a tapered end adapted to enter the conical aperture in the first head, a spring held clamping ring mounted on the second forming head, means for supporting a hose toe protector blank between the forming heads and a plunger operating through both forming heads for moving the hose toe protector blank through the first mentioned forming head.

2. In a machine of the class described, a pair of forming heads adapted to coöperate with one another for receiving and forming circular blanks of material into thimble shaped members, and a spring-held collar mounted for partial rotation on one of said forming heads, which collar engages and crimps the edges of the blanks positioned between the forming heads.

3. In a machine of the class described, a forming head having a conical recess, the surface of which is provided with radially arranged grooves, a second forming head having one end adapted to enter the conical recess in the first mentioned head, means for moving the second mentioned head toward the first mentioned head, and means for imparting partial rotary movement to the second mentioned head, when the forward end thereof is moved into the conical recess in the first mentioned head.

4. In a machine of the class described, a forming head having a conical aperture, the surface of which is provided with radially disposed grooves, a second forming head having a tapered end adapted to enter the conical aperture in the first head, radially arranged ribs formed on the tapered end of the second head, which ribs are adapted to enter the grooves in the conical aperture of the first mentioned head, means whereby the second mentioned forming head is partially rotated while its tapered end occupies the conical aperture, a spring held loosely mounted on the second mentioned head for engaging the marginal edge of the blank section of material positioned between the forming heads and a plunger operating through both forming heads for forcing the blank section of material through the first mentioned forming head.
5. In a machine of the class described, a forming head having a conical recess the surface of which is provided with radially arranged grooves, a second forming head having one end adapted to enter the conical recess in the first mentioned head, means for moving the second mentioned head toward the first mentioned head, means for imparting partial rotary movement to the second mentioned head, when the forward end thereof is moved into the conical recess in the first mentioned head, means yieldingly mounted upon the second mentioned head for clamping the marginal edge of the section of material of which the protector is formed against the face of the first mentioned head, and means operating through both heads for moving the section of material which forms the protector from position between the heads through one of said heads.
6. In a machine of the class described, a forming head having a conical aperture, the surface of which is provided with radially disposed grooves, a second forming head having a tapered end adapted to enter the conical aperture in the first head, radially arranged ribs formed on the tapered end of the second head, which ribs are adapted to enter the grooves in the conical aperture of the first mentioned head, a spring pressed ring mounted on the forward end of the second mentioned head, which ring is adapted to engage the face of the first mentioned head around the conical aperture therein for engaging the marginal edge of the section of material of which the protector is formed, and means whereby the second mentioned head is partially rotated independently of said ring when the forward end thereof occupies the conical aperture in the first mentioned head.
7. In a machine of the class described, the combination with a pair of forming heads adapted to form thimble-shaped hose toe protectors from blank sheets of material, of a tubular bearing coöperating with one of said heads, through which the hose toe protectors are forced after being formed by said heads, a tubular member adapted to receive the hose toe protectors from the tubular bearing, and a head movably positioned within said tubular member for supporting the hose toe protectors as they are forced thereinto.
8. In a machine of the class described, the combination with a pair of forming heads adapted to engage round sheets of material and corrugate the edges thereof to form thimble-shaped hose toe protectors, of a tubular member adapted to receive the thimble-shaped protectors from the forming heads, and a head mounted to move rearwardly within said tubular member for supporting the protectors while being packed therein.
9. In a machine of the class described, the combination with a pair of forming heads adapted to form thimble-shaped hose toe protectors from blank sheets of material, a tubular member connected to one of said forming heads and adapted to receive the hose toe protectors after the same are formed, means for forcing the protectors through one of the forming heads into the tubular packing member, and yielding means within the tubular packing member for supporting the protectors in nested form within said packing member.
10. In a machine of the class described, the combination with a pair of forming heads adapted to form thimble-shaped hose toe protectors from blank sheets of material, a tubular member connected to one of said forming heads and adapted to receive the hose toe protectors after the same are formed, means for forcing the protectors through one of the forming heads into the tubular packing member, yielding means within the tubular packing member for supporting the protectors in nested form within said packing member, and means whereby said supporting member is intermittently moved rearwardly through the packing member as the protectors are forced thereinto.
